(57) **CLAIM**

The ornamental design for an integrated circuit tag, as shown and described.

DESCRIPTION

FIG. 1 is a front elevational view of and integrated circuit tag showing my new design;

FIG. 2 is a top plan view thereof;

FIG. 3 is a left side elevational view thereof;

FIG. 4 is a right side elevational view thereof;

FIG. 5 is a rear elevational view thereof; and,

FIG. 6 is a bottom plan view thereof;
